UNITED STATES PATENT OFFICE.

GUSTAV BERNHARD PETSCHÉ, OF PHILADELPHIA, PENNSYLVANIA, AS-SIGNOR TO SOUTHWARK FOUNDRY & MACHINE COMPANY, OF PHILADELPHIA, PENNSYLVANIA, A CORPORATION OF PENNSYLVANIA.

PUMP.

No. 850,178.

Specification of Letters Patent.

Patented April 16, 1907.

Application filed April 22, 1903. Serial No. 153,776.

To all whom it may concern:

Be it known that I, GUSTAV BERNHARD PETSCHÉ, a subject of the Emperor of Germany, residing in the city and county of Philadelphia, in the State of Pennsylvania, have invented a certain new and useful Improvement in Pumps, of which the following is a true and exact description, reference being had to the accompanying drawings, which form a part thereof.

My invention relates to the actuation of the admission and delivery valves in pumps, particularly those having sliding gridiron-valves, and is especially adapted and intended for use in connection with air-pumps, such as are known as "compressing" or "blowing" engines, though in many of its features it is also adapted for use in connection with pumps used for propelling incompressible fluids.

My invention is also especially adapted and intended for use in connection with pumps actuated by means of gas or similar engines, which have less adaptability to meet conditions which impose upon the motor work in excess of that for which it is especially designed and adapted than is the case with steam-engines of the usual construction; and the object which I have especially in view is to so construct the pump having sliding gridiron-valves and its admission-valves so connected with the engine as to move in a fixed relationship with the propelling-piston of the pump that the time of closing of the admission-valve can be retarded at will, so as to lighten the work by imposing upon the propelling-piston the labor of propelling or compressing only a portion of the full charge of the pump-cylinder.

Other objects which I have in view are to provide an exceedingly simple and efficient mechanism for operating at the same time both the peculiar mechanism of the admission-valve and the certain valve-operating devices acting upon the delivery-valve. This and other features of my invention will be best understood as described in connection with the drawings, in which they are illustrated, and in which—

Figure 1 is a plan view of a blowing-engine provided with my improvements; Fig. 2, a side elevation of the engine; Fig. 3, an end view, on an enlarged scale, with the plate

covering an aperture in the receiver removed and the valve-actuating mechanisms shown in section. Fig. 4 is a perspective view showing the mechanism for actuating the admission-valve; Fig. 5, an elevation illustrating a modification of the mechanism for actuating the admission-valve; Fig. 6, a diagram or card illustrating the operation of the engine and different adjustments of the admission-valve. Fig. 7 is a sectional view of the hand-wheel connection shown in Fig. 3 and used in connection with the mechanism for adjusting the motions of the admission-valve. Fig. 8 is a diagram illustrating the operation of the admission-valve-adjusting mechanism, and Fig. 9 a diagram illustrating the operation of the mechanism for closing the delivery-valve.

A indicates the base or foundation of the engine; B, a gas-engine, which may be of any convenient construction.

C is a connecting-rod coupling the piston (not shown) with crank D on the main shaft E of the engine, F being a fly-wheel secured on said shaft, and G a bevel-gear also secured on said shaft and driving, through a bevel G', the shaft G'', by which motion is communicated in the design shown both to the valves of the gas-engine and the valves of the blowing-engine proper. As shown, a gear G³ on the shaft G'' drives, through a gear G⁴, the shaft G⁵, (best shown in Fig. 2,) which shaft has secured to it cams G⁶ and G⁷, which actuate the valve system (generally indicated at H) of the gas-engine. The shaft G'' also actuates, through a gear G⁸, secured to it, and an engaged gear G⁹, the shaft G¹⁰, which shaft has secured to it the eccentrics, (indicated at G¹¹ and G¹²,) which eccentrics, as will hereafter be described, actuate the mechanism which gives motion to the admission-valve in both directions and that which actuates the delivery-valve to close it.

I is a piston-rod directly connecting the piston of the gas-engine with the propelling-piston (not shown) of the pump or compressing-engine, said piston being in the pump-chamber, (indicated at J,) J'J' indicating the receiving-chambers at each end of the chamber J, and J² the connecting chamber or conduit which couples these chambers J' together.

The pump-chamber J is provided with admission-ports at both ends, one being indi-

cated at *k* in Fig. 3, while the admission-valve, lying inside of these ports, may be taken as indicated at *K* in the same figure. The chamber has also delivery-ports at both ends, the port system being indicated at *l* in Fig. 3 and the delivery-valve, working on the outside of these ports and in the receiver, being indicated at *L*.

K' indicates the valve-rod of the admission-valve, and *L'* the valve-rod of the delivery-valve. The valve-rod *K'* is, as shown, connected with a slide *M*, suitably guided and supported and supporting a pivot-pin *M'*, by which it is connected through a pivot-link *N* with a pivot-pin *O'* of link *O*, the lower end of which is coupled with the eccentric *G*¹¹, so as to have imparted to it a circular motion, while its upper end is connected with a device which will guide it in a reciprocatory path. As shown, the connection is made through a pivot-pin *O*² with a link *P*, pivoted at *P'* on an arm *Q*, which arm is secured to a rock-shaft *Q'*, having also secured to it the adjusting-lever *Q*², having the forked ends (indicated at *Q*³) and which (see Figs. 3 and 7) connect with trunnion extensions *S*⁹ *S*⁹ of a ring *S*⁸, held in a groove *S*⁴ of an annular internally-threaded block, (indicated at *S*³), screwing upon a threaded rod *S'* and having a sleeve extension *S*², to the end of which is connected the hand-wheel *S*⁵, the sleeve extension being preferably slit longitudinally, as indicated in Fig. 3, and provided with a taper-thread *S*⁶, upon which screws a clamping-nut, (indicated at *S*⁷).

Passing now to the mechanism connected with the delivery-valve, it will be seen (see Fig. 3) that the valve-stem *L'* has secured to its end the piston *T*, having projecting from its outer face the hollow cylindrical extension *T'*. The piston *T* moves in a valve-actuating cylinder, (indicated at *U*), and which, as shown, has its front or inner end connected through a conduit *U*⁵ with the pump-chamber *J*, a check-chamber (indicated at *U*⁶) being situated in the conduit. The outer head *U*⁷ of the cylinder is formed with a cylindrical extension of smaller diameter than the cylinder *U*, in which fits the hollow cylindrical extension *T'* of the piston, and a choke and non-return device *U*⁴ is provided, connecting with the outer end of the cylinder *U*. In the hollow cylindrical extension *T'* of the piston moves the valve-closing slide, (indicated at *U*²), said slide being preferably made hollow, as shown, and carrying a pivot-pin *U*³, to which is connected one end of the link *V*⁴, pivoted at its outer end to an oscillating arm *V*², secured on a rock-shaft *V'*, supported on brackets (indicated at *V*) and extending out from the edges of the cylindrical extension of the head *U*⁷. The rock-shaft *V'* has also secured to it a lever-arm *V*³, to the end of which is connected the link *Z*, the other end of which is secured by

an eccentric-ring to the eccentric *G*¹². This delivery - valve mechanism is shown here simply as a part of the engine illustrated and because in its combination with the admission-valve mechanism it forms a feature of this invention. Separately it forms the subject-matter of my divisional application, filed May 11, 1904, Serial No. 207,379, and its broader features constitute the subject-matter of my Patent No. 784,122, of March 7, 1895.

In Fig. 5 of the drawings I have illustrated a modification in which in place of actuating the adjusting-lever *Q*² by the mechanism described in connection with Figs. 3 and 7 I have provided for the automatic operation of this lever and the parts connected therewith, the lower end of the lever being connected through a link *W* with a piston-rod *W'* secured to a piston *W*², moving in a cylinder *W*³, and normally thrust forward by the action of the spring *W*⁴, a conduit *j* leading from the front end of the cylinder *W*³ to the receiver *J'* of the engine or a part in constant communication therewith. A rear extension of the rod *W'* has secured to it a piston *W*⁵, working in the cylinder *W*⁶, the ends of which are connected by a conduit *W*⁷, in which is situated a regulating-cock *W*⁸. In this diagrammatically-illustrated modification the spring *W*⁴ is of sufficient strength to hold the parts normally and under ordinary conditions in the position indicated; but when the pressure in the receiver rises above normal it will be communicated through the conduit *j* to the front end of the cylinder *W*³ and will move the piston *W*² backward to a degree proportionate to the excess of pressure in the receiver. The cylinder *W*⁶ is filled with oil or other fluid, the flow of which from one end to the other is regulated by the adjustments of the cock *W*⁸, and this device serves simply as a steady-ing device, preventing unduly rapid movements of the piston-rod *W'*.

The operation of the admission-valve-actuating mechanism is indicated in the diagram, Fig. 8, the lines of which, correspond to mechanical parts of the apparatus, are similarly lettered, and it will be seen that in normal adjustments—to wit, that which causes the admission-valve to open and close at the ends of the stroke of the propelling-piston—the pivot-pin *O'* will at each rotation of the eccentric *G*¹¹ describe the path indicated at *x*, the point *x'* indicating that on which the valve *K* has just closed port *k*, while the point *x*² indicates approximately the point at which the valve will begin to open, the valve moving through this lap during the passage of the point *O'* from *x'* to *x*², over the portion of the curve indicated at *x*³, the greater portion of which, it will be observed, is of such form that the valve will practically remain stationary after having

5 moved over its lap and before again moving over its lap to open. It will also be observed that in normal adjustment, as shown in the diagram, the point of greatest eccentricity of the eccentric G^{11} lies at the point X when the valve is edge and edge in the act of closing, as shown in the diagram.

10 Referring now to the adjustment of parts indicated in dotted lines in Fig. 8, it will be seen that by shifting the adjusting-lever Q^2 through the arc indicated, and consequently shifting the other parts, as also indicated, the figure y' , which will now be described, by the pivot-point O', will be such as to defer the 15 closing action of the valve with reference to the positively-moving parts of the engine, including the propelling-piston, so that the closure will take place at the point indicated at y' which corresponds with the location of 20 the point of greatest eccentricity in the eccentric at the point indicated at Y, and it will be understood that in this adjustment the admission-valve will not close until the propelling-piston has moved through a distance 25 in the pump-chamber corresponding to the arc between the points X and Y in the diagram, the fluid propelled by it while moving this distance escaping freely through the admission-valve and the actual work not beginning 30 until the admission-valve has closed, these conditions being obviously such that the engine will be able to propel or compress the reduced quantity of fluid against a pressure in excess of that for which the engine is 35 normally adjusted and at which it is capable of propelling the entire contents of the pump-chamber. It will also be seen that my valve-actuating mechanism is of such a character that the upper ends of the figures x and y 40 practically coincide with each other, so that the point y' , indicating the point at which the admission-valve will open, practically coincides with the point x^2 .

45 In further explanation of the action of the adjustments in the motions of the admission-valve I would refer to the diagram marked Fig. 6, in which the line 1 2 indicates the total travel of the compressing-piston, the line 1 3 indicates the normal resistance to be 50 overcome, and the figures 1 2 3 4 the work performed under normal conditions. Obviously, if the working travel of the piston is reduced by the described adjustments of the admission-valve to an extent indicated by 55 the line 2 5, corresponding to an increase in resistance indicated by the line 3 6, then the work performed by the engine under its new adjustment will be indicated by the figure 1 5 6 7 of equal area to the figure 1 2 3 4. 60 The operation of the delivery-valve mechanism is easily followed on Figs. 1, 3, and 9. The delivery-valve is closed when the propelling-piston begins its motion toward said valve and is opened by the action of fluid 65 under pressure admitted to the actuating-

cylinder U. In the construction illustrated the air in the cylinder J passes through conduit U³ into the valve-actuating cylinder from the beginning of the compressing stroke of the piston, but so long as the delivery-valve is held to its seat by pressure in the receiver of the engine materially in excess of that in the blowing-cylinder the frictional resistance will prevent the movement of the valve, which, however, moves with great 75 rapidity when the pressure upon its face and back become approximately equal. At the close of the compressing stroke of the piston the eccentric G^{12} and its connections Z, V³, V², and V⁴ act upon the slide U², pushing it 80 inward against the piston T and moving the valve to a closed position. The connection of the link V⁴ and the oscillating movement imparted to the arm V² are such that in moving from the position indicated in full lines in 85 the diagram, Fig. 9, which is that in which the valve is edge and edge in closing, to the position in which the link V² is horizontal, the valve will simply move over its lap. The further downward movement of the arm V² 90 will in no wise affect the position of the valve, nor is it affected by the upward movement of the arm, which, after passing the horizontal position, retracts the closing-slide and acts simply to shift it out of the way and leave 95 the valve free to move under the influence of its actuating-cylinder, the succeeding downward movement of the oscillating arm acting, as already described, to close the valve.

100 The choke-conduits (indicated at U⁴ and u⁴) are provided for the purpose of cushioning the outward movement of the actuating-piston, both with regard to the rear side of the actuating-cylinder and with regard to the closing-slide, which in a blowing-engine 105 will not always be retracted to its full extent when the valve is opened. In my application filed April 23, 1903, I have described and shown mechanism for closing the delivery-valve of a generally similar character to that 110 hereinabove described except that the closing-slide is connected by means of a link V⁴ with a slide reciprocating in a straight line.

115 Having now described my invention, what I claim as new, and desire to secure by Letters Patent, is—

1. In a pump having an admission-valve, the device for operating said valve and varying its time of closing, consisting of a link O, means for imparting to one end of said link a 120 constant rotary motion, means for guiding the other end of said link through a reciprocating path, means for shifting said guiding device to vary the motion of the link, and a link N, pivotally connected to an intermediate point on the link O, and to the admission-valve rod. 125

2. In a pump having an admission-valve, the device for operating said valve and varying its time of closing, consisting of a link O, 130

means for imparting to one end of said link a constant rotary motion, means for guiding the other end of said link through a reciprocating path, means for shifting said guiding device to vary the motion of the link, a link N, pivotally connected to an intermediate point on the link O, and to the admission-valve rod, and means actuated by the pressure of the receiver in the pump, for shifting the guiding device aforesaid to vary the closing of the valve.

3. In a pump having an admission-valve, the device for operating said valve and varying its time of closing, consisting of a link O, means for imparting to one end of said link a constant rotary motion, a link P, pivoted to the other end of link O, and to a movable pivot P', means for shifting the position of the movable pivot P', to vary the motion of

link O, and a link N, pivotally connected to 20 an intermediate point on the link O, and to the admission-valve rod.

4. In a pump having an admission-valve, the device for operating said valve and varying its time of closing, consisting of a link O, 25 means for imparting to one end of said link a constant rotary motion, a rock-shaft Q', an arm Q, secured to said shaft, a link P, pivoted to the arm Q, and to the end of link O, means for turning the rock-shaft and thus 30 varying the position of the pivot on arm Q, and a link N, pivotally connected to an intermediate point on the link O, and to the admission-valve rod.

GUSTAV BERNHARD PETSCHE.
